UNITED STATES PATENT OFFICE.

HENRY F. CRANDALL, OF MILWAUKEE, WISCONSIN, ASSIGNOR TO THE MILWAUKEE HARVESTER COMPANY, OF SAME PLACE.

WINDLASS.

SPECIFICATION forming part of Letters Patent No. 380,995, dated April 10, 1888.

Application filed November 14, 1887. Serial No. 255,065. No model.)

To all whom it may concern:

Be it known that I, HENRY F. CRANDALL, of Milwaukee, in the county of Milwaukee, and in the State of Wisconsin, have invented certain new and useful Improvements in Windlasses; and I do hereby declare that the following is a full, clear, and exact description thereof.

My invention relates to windlasses, and will be fully described hereinafter.

In the drawings, Figure 1 is a side elevation of my device with the axle in cross-section. Fig. 2 is a like elevation, but with the parts in a different position and a portion of one of the jaws of the operating-lever broken away. Fig. 3 is a section on line 3 3, Fig. 1; and Fig. 4 is a perspective view of a pawl forming part of my invention.

A is the support for the bearings *a* of one end of the axle B, the other end of which is supported in a like bearing. (Not shown.) C is a casting that forms part of the operating-lever, of which C' is the handle. The casting C is formed with two jaws, *b* *b'*, both of which are slotted, as at *c* *c*, to receive the axle B, and between the jaws the axle carries a ratchet-wheel, D. The portion of casting C that connects jaws *b* *b'* is formed with a dog, *d*, and on its inner face the casting C carries a curved arm, *e*, and on its lower edge jaw *b'* has a finger, *f*. A pawl, E, is pivoted to the support A, or to a flange on the plate *a'* of the bearing *a*, and this pawl has a heel, *g*, to receive the rounded end of a spindle, *h*, that carries a spring, *i*, the rear end of the spindle sliding freely through an opening in a lug, *j*.

K is a stop to limit the backward throw of the pawl E, and the position of the spindle with relation to pawl E is such that when the latter is in the position shown in Fig. 2 the spring will have a tendency to hold it in that position, as its force is then directed below the dead-center; but when the pawl is tilted forward to or beyond a vertical, then the force of the spring will serve to hold it forward in the position shown in Fig. 1.

m is a lug that projects forward and upward from pawl E in position to be struck by the finger *f* of jaw *b'* when the lever C C' is shifted from the position shown in Fig. 1 to that in Fig. 2.

Operation. When the parts are in the position shown in Fig. 1, the dog *d* of levers C C' is in position to engage the teeth of ratchet-wheel D as the lever is drawn in the direction of the arrow, and the pawl E is also in position to engage said teeth to form a stop when the ratchet-wheel is released by the dog of the lever; hence the ratchet-wheel and axle may be turned by reciprocating the lever on an arc of a circle inside of the vertical plane of the axis of the axle, the dog *d* engaging with a tooth of the ratchet-wheel to turn the axle at each forward movement of the lever, while the slots permit the lever to rise so that the dog may slide over the ratchet-teeth at each backward movement of the lever, the pawl E acting as a stop to hold the ratchet while the lever is being thrown back for a new grip, and to hold the ratchet when the lever is released. When the axle is to be permitted to turn in the opposite direction, or backward, for instance, to unwind a rope that has been wound upon it to lower a body suspended from said rope, the lever C' is drawn forward of the vertical plane of its axis, and the finger *f*, striking the lug *m* of the pawl, will throw the latter back into the position shown in Fig. 2 and out of the line of travel of the teeth, where it will be held by the spring *i* and its spindle. The lever C' may now be thrust inward until the arm *e* strikes pawl E and throws it forward against the ratchet-wheel, and as the ratchet-wheel follows the dog *d* the ratchet-wheel will be carried back one notch by the weight on the axle, and if the axle is to be further unwound the lever C' is lifted until the dog *d* clears the ratchet-teeth, and then it (the lever,) is dropped as far as the slots *c* will permit it to go, and then its upper end is drawn forward until the finger *f* throws pawl E out of the way, when the axle may be further unwound by again thrusting the lever inward, and this is repeated until the axle has been sufficiently unwound.

My device is more particularly designed to operate in connection with harvesters for the purpose of raising and lowering the latter; but I do not mean to confine the use of said device to any special class of machinery or to the identical contour or construction of the parts, as these may be varied without departing from the spirit of my invention.

Having thus fully described my invention, what I claim as new, and desire to secure by Letters Patent, is—

1. The combination, with the axle and ratchet-wheel, of the lever and its slotted jaws, one of which has a finger projecting from its lower edge, and a spring-pawl for engagement with the teeth of the ratchet-wheel, said pawl having a lug for engagement with the jaw-finger, ¹⁰ as set forth.

2. The combination, with the ratchet-wheel and axle, of a lever and its slotted jaws and dog for engaging the teeth of the ratchet-wheel, a finger depending from one of the jaws, ¹⁵ a spring-pawl for engaging the teeth of the ratchet-wheel, and a lug projecting from the

spring-pawl in the path of the finger of the jaw, substantially as set forth.

3. The combination, with the lever, ratchet-wheel, jaws, and spring-pawl, of an arm projecting from the rear of the casting, of which the jaws form a part, and a stop for limiting the inner movement of the arm, substantially as set forth. ²⁰

In testimony that I claim the foregoing I ²⁵ have hereunto set my hand, at Milwaukee, in the county of Milwaukee and State of Wisconsin, in the presence of two witnesses.

HENRY F. CRANDALL.
